UNITED STATES PATENT OFFICE.

ALBERT P. THURSTON, OF LONDON, AND HAMILTON N. WYLIE, OF BIRMINGHAM, ENGLAND.

COMPOUND METAL SPAR.

Application filed December 10, 1919. Serial No. 343,890.

To all whom it may concern:

Be it known that we, ALBERT PETER THURSTON, of the Royal Flying Corps Club, Bruton Street, London, W., captain in the 5 Royal Air Force, and HAMILTON NEIL WYLIE, of 109 Colmore Row, Birmingham, England, major in the Royal Air Force, subjects of the King of the United Kingdom of Great Britain and Ireland, have invented 10 new and useful Compound Metal Spars, of which the following is a specification.

This invention relates to compound metal spars and like structural members suitable for use as wing spars in aircraft and for 15 other structural purposes.

The invention relates more particularly to spars of girder formation which comprise oppositely disposed hollow booms or flanges connected by webs and adapted 20 to resist longitudinal compression and tension stresses.

Stated broadly this invention contemplates a compound metal spar having a plurality of hollow booms or flanges symmetrically or otherwise disposed about a 25 plurality of sheet metal webs. Stated another way this invention consists of a plurality of hollow compression members and a plurality of hollow tension members 30 connected by sheet metal webs to form a compound spar.

This invention may be more particularly stated to consist of a sheet metal structure comprising a plurality of web members connected together in the median plane of the structure and disposed in splayed relationship and forming a number of projecting arms in cross section, and tubular flange members located along the outer edge of 40 said projecting arms respectively, said tubular flange members being constituted of loops having outwardly curved extremities connected to the said respective projecting arms.

An important feature of this invention 45 is the curving outwards of the free edges of the flange members and other parts of the structure in the vicinity of joints.

Further features of this invention will 50 transpire in the following description of the accompanying drawings, in which:

Figure 1 is a view in cross section of one form of construction.

Figure 2 is a view in cross section of another embodiment,

Figure 3 is a view illustrating one form of reinforcement for the spar shewn in Figure 1,

Figure 4 is a fragmentary detail of Figure 3 in elevation from the view-point indicated by its arrow, 60

Figure 5 is a view in cross section of a further modification.

Referring to Figure 1, two hollow compression members 1 and 2 are connected to 65 two hollow tension members 3 and 4 by means of webs 5 and 6 respectively. In the form shewn the hollow members are formed by rolling the edges of the webs into tubular form and riveting, welding or otherwise securing the edges as at 7. The webs 5 and 6 are similarly secured at or near the centre line of the spar as shewn at 8. This construction consists of two similar sections 70 one of which is reversed, and lends itself admirably to the employment of standard sections of rolled sheet metal used in the manufacture of tire rims. 75

The reinforcement for such a spar is shewn in Figure 3 and consists of rigid frames or 80 ribs 9 fitting snugly and secured by screws, rivets or other means to the webs 5 and 6. These reinforcements are disposed at suitable intervals throughout the length of the spar. The frames or ribs 9 may be solid or 85 of ring or open form and may consist of metal wood or any other suitable rigid material. The rivets 7 in certain forms of construction may be employed for securing not only the rolled edge of the web but also the 90 frame or rib 9 as shewn in Figure 3.

Further reinforcement, if required, is obtained by fitting a steel band 10 to embrace the spar, and distance pieces 11 fitting the 95 hollows in the webs and then tightening up the band by means of a bolt 12. Tangs 13 may be pressed out of the steel band 10 or may be otherwise formed and secured thereto as shewn in Figure 4. These tangs serve in the case of wing spars for aircraft for securing the wing ribs to the spar. 100

Referring to Figure 2 the hollow compression members 1 and 2 are connected by a web 14 and the members 3 and 4 are connected by a web 15. A third web 16 connects the transverse webs 14 and 15 together the several webs being secured as shewn. This construction is suitable for large aeroplane spars and the flattened hollow booms or flanges touch each other at the top and 110

bottom of the spar. The major axes of these hollow members are symmetrically inclined to the central vertical plane of the spar, and they are corrugated longitudinally so that their cross sections have three lobes.

The arrangement of Figure 5 shews webs connecting the four hollow members. Webs 17, 18, 19 and 20 have one edge embraced by and secured to the edges of each hollow member respectively whilst web 21 is secured between adjacent edges of the above mentioned webs. This arrangement facilitates manufacture and possesses the advantage that owing to the spacing apart of the hollow members resistance to side bending is relatively great.

The construction shewn in Figures 2 and 5 may be reinforced in a manner similar to that described with reference to Figure 3.

In all cases the hollow members and webs are suitably corrugated parallel to their length so that they may be made of sheet metal of small gauge yet sufficiently strong to withstand shear and compression forces due to lead on the spar.

To prevent buckling of the edges of the flange members, webs and distance pieces they are preferably curved outwards as shewn in the drawings.

The hollow members are formed separately or integral with the webs according to circumstances and torsional rigidity is imparted to them by riveting or otherwise securing their edges.

When three hollow members only are employed in constructing the spar the number and disposition of the webs is modified accordingly.

In all cases the webs may consist of two or more parts suitably connected together the compound webs being of a single thickness of metal.

We claim.

1. A sheet metal structure comprising a plurality of web members connected together in the median plane of the structure and disposed in splayed relationship and forming a number of separate projecting arms in cross section, a tubular member located along the outer edge of each of said projecting arms, and a plurality of reinforcing cross frames disposed at intervals between said projecting arms.

2. A sheet metal structure comprising a plurality of longitudinally corrugated web members connected together in the median plane of the structure and disposed in splayed relationship and forming a number of separate projecting arms in cross section, a tubular member located along the outer edge of each of said projecting arms, and a plurality of reinforcing members disposed at intervals between said projecting arms.

3. A sheet metal structure comprising a

plurality of web members connected together in the median plane of the structure and disposed in splayed relationship and forming a number of separate projecting arms in cross section, a tubular member located along the outer edge of each of said projecting arms, a plurality of reinforcing cross frames disposed at intervals between said projecting arms, straps disposed at intervals embracing said web members, and means for tightening said straps.

4. A sheet metal structure comprising a plurality of longitudinally corrugated web members connected together in the median plane of the structure and disposed in splayed relationship and forming a number of separate projecting arms in cross section, a tubular member located along the outer edge of each of said projecting arms, a plurality of reinforcing members disposed at intervals between said projecting arms, straps disposed at intervals embracing said web members, and means for tightening said straps.

5. A sheet metal structure comprising a plurality of longitudinally corrugated web members connected together in the median plane of the structure and disposed in splayed relationship and forming a number of projecting arms in cross section, a tubular member located along the outer edge of each of said projecting arms, and a plurality of reinforcing members disposed at intervals between said projecting arms.

6. A sheet metal structure comprising a plurality of web members connected together in the median plane of the structure and disposed in splayed relationship and forming a number of projecting arms in cross section, a tubular member located along the edge of each of said projecting arms, a plurality of reinforcing members disposed at intervals between said projecting arms, straps disposed at intervals embracing said web members, and means for tightening said straps.

7. A sheet metal structure comprising a plurality of centrally connected web members disposed in splayed relationship and forming a number of projecting arms in cross section, one longitudinal tubular member located along the outer edge of each of said projecting arms, and a plurality of reinforcing cross frames disposed at intervals between said projecting arms.

8. A sheet metal structure comprising a plurality of longitudinally corrugated centrally connected web members disposed in splayed relationship and forming a number of separate projecting arms in cross section, a longitudinal tubular member terminating each of said projecting arms along the outer edge thereof, and a plurality of reinforcing members disposed at intervals between said projecting arms.

9. A sheet metal structure comprising a

plurality of centrally connected web members disposed in splayed relationship and forming a number of separate projecting arms in cross section, one longitudinal tubular member terminating each of said projecting arms along the outer edge thereof, a plurality of reinforcing cross frames disposed at intervals between said projecting arms, straps disposed at intervals embracing said web members, and means for tightening said straps.

10. A sheet metal structure comprising a plurality of longitudinally corrugated centrally connected web members disposed in splayed relationship and forming a number of separate projecting arms in cross section one tubular member terminating each of said projecting arms along the outer edge thereof, a plurality of reinforcing members disposed at intervals between said projecting arms, straps disposed at intervals embracing said web members, and means for tightening said straps.

11. A sheet metal structure comprising a

plurality of web members disposed in splayed relationship and forming a number of projecting arms in cross section, means for connecting said web members together along a central line, one tubular member along the outer edge of each of said projecting arms, and a plurality of reinforcing members disposed at intervals between said projecting arms.

12. A sheet metal structure comprising a plurality of web members disposed in splayed relationship and forming a number of projecting arms in cross section, means for connecting said web members together along a central line, one tubular member along the outer edge of each of said projecting arms, a plurality of reinforcing members disposed at intervals between said projecting arms, straps disposed at intervals embracing said web members and means for tightening said straps.
